US00D954522S

(12) **United States Design Patent** (10) Patent No.: **US D954,522 S**
(45) Date of Patent: **** Jun. 14, 2022**

(54) **SAFETY HAMMER**

(71) Applicant: **DOGA S.A.**, Abrera (ES)

(72) Inventors: **Antoni García Coma**, Abrera (ES);
Marie Le Monnier, Abrera (ES)

(73) Assignee: **DOGA S.A.**, Abrera (ES)

(**) Term: **15 Years**

(21) Appl. No.: **35/511,579**

(22) Filed: **Mar. 4, 2021**

(80) **Hague Agreement Data**

Int. Filing Date: **Mar. 4, 2021**

Int. Reg. No.: **DM/213077**

Int. Reg. Date: **Mar. 4, 2021**

Int. Reg. Pub. Date: **Mar. 19, 2021**

(51) **LOC (13) Cl.** 29-02

(52) **U.S. Cl.**

USPC **D8/81**; D29/124

(58) **Field of Classification Search**

USPC D8/75, 81, 105, 346; D29/124

CPC B25D 2250/271

See application file for complete search history.
